(57) **CLAIM**

The ornamental design for an embossing pattern for an absorbent article, as shown and described.

DESCRIPTION

FIG. 1 is a top plan view of our new embossing pattern for an absorbent article, the absorbent article being in the form of a sanitary napkin, which is shown in phantom and forms no part of the invention;

FIG. 2 is a bottom plan view thereof;

FIG. 3 is a front elevation thereof;

FIG. 4 is a rear elevation thereof;

FIG. 5 is a left side elevation thereof, the right side elevation, which is not shown, is substantially the same as the left side elevation;

FIG. 6 is a cross-section taken along line 6—6 of FIG. 1; and,

FIG. 7 is a perspective view thereof.
